UNITED STATES PATENT OFFICE.

WALTER E. HOSCH, OF ST. LOUIS, MISSOURI; ANNIE MAE HOSCH, ADMINISTRATRIX OF SAID WALTER E. HOSCH, DECEASED, ASSIGNOR TO THE MEASUREGRAPH COMPANY, OF ST. LOUIS, MISSOURI, A CORPORATION.

COUNTER APPARATUS.

1,343,723.

Specification of Letters Patent. Patented June 15, 1920.

Application filed February 13, 1918. Serial No. 216,954.

To all whom it may concern:

Be it known that I, WALTER E. HOSCH, a citizen of the United States, residing in the city of St. Louis and State of Missouri, have invented new and useful Improvements in Counter Apparatus, of which the following is a specification.

This invention relates to apparatus for facilitating the sale of piece goods such as cloth, ribbons, laces, etc., when sold over the counter. The general object of the invention is to provide apparatus which will enable the measuring machine to be held so as to coöperate with the counter in measuring the goods, but operating in such a way so as to permit the depression of the measuring machine into the counter, so that when the measuring machine is not in use, the upper surface of the counter is left unobstructed.

Further objects of the invention will appear hereinafter.

The invention consists in the general combination of parts and simplicity of details described in the following specification, all of which contribute to produce an efficient counter apparatus.

In the drawing which fully illustrates the preferred embodiment of my invention,

Figure 1 is a plan of a counter embodying my invention;

Fig. 2 is a vertical section taken on the line 2—2 of Fig. 1, upon a larger scale, certain parts being broken away, and further illustrating details of the construction; this view shows the measuring machine depressed in such a way as to leave the upper surface of the counter unobstructed;

Fig. 3 is a vertical section on the line 3—3 of Fig. 1, illustrating the machine in its elevated and active position, in which position it coöperates with the counter to support and measure the goods; and

Fig. 4 is a horizontal section taken on the line 4—4 of Fig. 2.

Referring more particularly to the parts, 1 represents a counter which may consist of a single fixed part, presenting a horizontal upper surface 2 upon which the bolt of cloth or other goods to be sold, may be supported.

The measuring machine illustrated is of a type which measures the length of the

cloth and also computes the charge to be made for any given length of goods to be sold. This machine is indicated by the numeral 3 and is substantially L shaped in plan. It is supported in an L shaped opening 4, formed through the counter. As the counter is a fixed part, it is evident that the edges of this opening are fixed, and the opening does not change in size. One of the extensions or legs 5 of the L extends at right angles to the longitudinal axis of the counter and is formed with a throat or gap 6 through which the edge of the goods 65 passes when the goods is pulled longitudinally along the counter to measure it. In passing through the throat or gap 6, the goods rotates a roller 7, the face of which is shown in Fig. 3, and this roller communicates its movements to a pointer on an indicating dial 8 on the upper side of the machine, which indicates the length of the goods measured, and it also communicates its motion to cost-indicating means 9. 75

This measuring machine is of the type illustrated in my copending application, Serial No. 6954, matured into Patent No. 1,298,162, dated March 25, 1919. On the vertical side walls of the case or casing 10 of these measuring machines, controlling means or parts are provided for controlling the operation of the mechanism on the interior of the case; in Fig. 3, for example, I have illustrated a thumb head 11 which connects in any suitable manner with the interior mechanism of the instrument. In order to enable the machine to descend into the opening 4 of the counter, this thumb head 11 is placed in a depression or recess 12 in the side wall of the case. I utilize a similar depression for every other exposed controlling part as illustrated in my said application, Serial No. 6954, but I have simply shown one of these controlling pieces here for illustration.

I provide means for supporting and guiding the measuring and computing machine 3, so that when desired it may be supported in a depressed position (see Fig. 2). In order to attain these results, I provide a guide which may be in the form of a U-shaped frame 13, the vertical members 14 of which are provided with feet 14a, at their

upper ends, which are attached to the under side of the counter. Each of these vertical members is provided on its inner face with a vertical guide slot 15, which is formed 5 within a suitable housing or channel 16.

The measuring machine 3, is supported on a carriage 17, in the form of a hollow block, which conforms in outline to the plan of the measuring machine. The side 10 walls of this carriage are provided with vertically disposed guide tongues 18, respectively, and each of these tongues runs freely in one of the guide slots 15. The inner face 19, of each the vertical members 15 of the U frame is substantially flush with the corresponding edge 20 of the opening 4 in the counter. When the machine is in its elevated position, the upper end of the carriage occupies the opening 4, and the 20 ends of the tongues 18 lie near the under face of the counter. They would prevent the carriage from passing up through the counter, accidentally. In this elevated position of the measuring machine, the upper face 21 of the carriage which is flat, will be substantially flush with the upper face of the counter 1, and coöperates with the counter to form a continuous horizontal support.

I provide means for counter-balancing 30 the weight of the machine and its carriage. For this purpose, I provide a counter-weight 22, supported by a cord 23, the loop of which passes over a small pulley 24 attached to the under side of the counter, the 35 other end of the cord being secured to a lug 25, projecting from the lower end of the carriage.

I provide means for holding the carriage and measuring machine fixed in an elevated 40 position such as shown in Fig. 3, or in a depressed position such as that shown in Fig. 2. In this latter position, the upper face of the measuring machine which is substantially flat is preferably substantially 45 flush with the upper face of the counter. In order to accomplish this, I provide the under side of the carriage with a small spring-pressed latch 26, having a finger lever or tail 27, for operating it. This latch 26 is 50 normally pressed by a leaf spring 28 in such a way that a pin 29 formed on the end of the latch, can engage with either one of the openings 30 and 31, the former of which is at the lower part of the U frame, and 55 the latter of which is at a more elevated position. Evidently the counter is unobstructed in any way when the machine is in its depressed position.

It is not necessary to fix the measuring 60 machine 5 to the upper face of the carriage, but I prefer to provide at least two dowel pins 32 (see Fig. 2) which are screwed into the under side of the casing 10, and which are received in corresponding openings or 65 sockets 33 in the upper face 21 of the car-

riage. These dowel pins prevent the measuring machine from becoming dislocated from its position on the carriage.

By reason of the fact that the upper portion of the carriage conforms in outline to 70 the shape of the opening in the counter, it is evident that when the carriage is held in its elevated position, if the measuring machine be removed, the upper face of the carriage will lie flush with the upper face of the 75 counter, thereby filling the counter opening; furthermore, as the dowel pins 32 are carried by the measuring machine, there will be no obstruction on the upper face of the counter after the measuring machine 80 has been removed.

It is understood that the embodiment of the invention described herein is only one of the many embodiments my invention may take, and I do not wish to be limited in the 85 practice of my invention nor in my claims, to the particular embodiment set forth.

What I claim is:

1. In apparatus of the class described, the combination of a counter consisting of 90 a single fixed part with an opening therethrough, and having a substantially horizontal upper surface for supporting goods, a guide secured to the underside of the counter, a carriage movably mounted in 95 said guide, and having a substantially flat upper face, a cloth measuring machine resting removably on the upper face of said carriage, said carriage and said measuring machine conforming in outline to said opening, means for holding the carriage with its upper face substantially flush with the upper face of said counter to hold said measuring machine in an operative position, and enabling the measuring machine 105 to be removed so as to permit the upper face of the carriage to coöperate with the upper face of the counter to form a continuous unobstructed supporting surface for goods on the counter, said means also operating 110 to hold the carriage in a depressed position with the upper face of the measuring machine substantially flush with the upper face of the counter so that the upper face of the measuring machine will coöperate 115 with the counter to form a continuous unobstructed supporting surface.

2. In apparatus of the class described, the combination of a counter consisting of 120 a single fixed part with an opening therethrough, and having a substantially horizontal upper surface for supporting goods, a guide secured to the underside of the counter, a carriage movably mounted in said guide and having a substantially flat upper 125 face with sockets therein, a cloth measuring machine resting removably on the upper face of said carriage having dowel pins received in said sockets, said carriage and said measuring machine conforming in out- 130

line to said opening, means for holding the carriage with its upper face substantially flush with the upper face of said counter to hold said measuring machine in an operative position, and enabling the measuring machine to be lifted off of the carriage, thereby permitting the upper face of the carriage to coöperate with the upper face of the counter to form a continuous unob-

- 10 structed supporting surface for goods on the counter, said means also operating to hold the carriage in a depressed position with the upper face of the measuring machine substantially flush with the upper 15 face of the counter so that the upper face of the measuring machine will coöperate with the counter to form a continuous unobstructed supporting surface.

3. In apparatus of the class described, 20 the combination of a counter presenting a substantially horizontal surface for supporting goods, and having an opening therein, a cloth measuring machine having a casing with side walls, and fitting said 25 opening, mounted to move through said opening into a depressed position below said counter, said machine having a controlling part for controlling the mechanism of said cloth-measuring machine, disposed 30 in the side wall of said casing, said side wall having a depression receiving said controlling part, whereby the side wall of said casing is unobstructed to permit the free movement of said casing through said 35 opening.

4. In apparatus of the class described, 40 the combination of a counter presenting a substantially horizontal surface for supporting goods and having an opening therein, a cloth measuring machine having a casing fitting said opening, and having a controlling part for the mechanism thereof set in the side wall of said casing so as to leave the side of said casing unobstructed,

means for supporting and guiding said 45 machine through said opening, means for holding said machine fixed in an elevated position above said counter to permit the cloth to be measured, and means for holding said machine in a depressed position 50 within said opening.

5. In apparatus of the class described, the combination of a counter having a substantially horizontal surface for supporting goods, and having an opening there- 55 through, a guide carried by the counter, a carriage movably mounted in the guide and having a substantially flat upper face, a cloth measuring machine resting upon the upper face of said carriage and having a 60 casing with vertical side walls, said casing conforming to the outline of said opening, said measuring machine having a controlling part for controlling the mechanism of the measuring machine, the side wall adjacent said controlling part having a depression receiving said controlling part, whereby the side wall of the casing is unobstructed to permit the free movement of the casing 65 through the opening, means for supporting the carriage with its upper face flush with the upper face of the counter to hold the measuring machine in an operative position and so that the measuring machine may be lifted off of the carriage to enable 70 the upper face of the carriage to coöperate with the upper face of the counter to form a continuous unobstructed supporting surface, said means also operating to support the carriage in a depressed position with 75 the upper face of the casing flush with the upper face of the counter so as to coöperate with the counter to form a continuous unobstructed supporting surface.

In testimony whereof I have hereunto set 80 my hand.

WALTER E. HOSCH.
